ELECTRICAL CONNECTER

Mortimer B. Cameron, Edgewood, Pa., assignor to
The Westinghouse Air Brake Company, Wil-
merding, Pa., a corporation of Pennsylvania

Application March 26, 1938, Serial No. 198,241

4 Claims. (Cl. 173—332)

This invention relates to automatic couplers for railway cars, and more particularly to an electrical connector mechanism adapted to be employed for connecting electric train line circuits between cars of a train.

The principal object of my invention is to provide an improved electrical connector device of the type adapted to be carried on an automatic coupler head, which device embodies a movable butt contact member having means associated therewith for establishing a secure but readily detachable connection between the contact member and the train wire or cable, and a weatherproof casing including a flexible shield adapted to prevent access of moisture to the interior of the device past the outer end of the movable contact member.

Other objects and advantages of my invention will appear in the following detailed description thereof, taken with reference to the accompanying drawing, wherein:

Fig. 1 is a plan view of a pair of operatively engaged car coupler heads showing my improved electrical connector mechanism applied thereto; Fig. 2 is an enlarged detail sectional view of an electrical connector constructed according to my invention; Fig. 3 is a fragmentary sectional view taken on the line 3—3 of Fig. 2; Fig. 4 is a fragmentary sectional view taken on the line 4—4 of Fig. 2; Fig. 5 is an elevational view of a portion of the clamping members shown in Figs. 2 and 3; and Fig. 6 is an enlarged detail view of the conical sleeve element shown in Fig. 2.

As shown in Fig. 1 of the drawing, an electrical connector 14 embodying the invention is applied to each of a pair of counterpart car and pipe coupling mechanisms comprising coupler heads 10 provided with inclined interengaging recesses 11 and projections 12. Each electrical connector 14 is mounted on the associated coupler head 10 in alignment with the projection 12 and recess 11 thereof, so that when the coupler heads on adjacent cars are brought into coupling engagement, the final movement as the coupler heads are locked together will be in the direction of the inclination of the recesses 11, with the result that the contact members of the connectors 14, hereinafter described, are firmly engaged.

Referring to Fig. 2 of the drawing, the electrical connector 14 comprises a tubular casing 15, preferably made of cast iron, having formed thereon a plurality of bracket lugs 16 which are suitably apertured for receiving bolts 17, by means of which the casing is mounted on the coupler head, as shown in Fig. 1. Formed within the tubular

casing 14 is a longitudinal bore 19, annular raised portions 20 of the wall of which bore are suitably finished to receive a cylindrical insulating member 21, which may be formed of any durable material such as "Bakelite", and which is adapted to have a snug fit with the portions 20 of the cylinder wall. A bushing 23 having several apertures is fitted within the longitudinal bore of the cylindrical member 21, this bushing being preferably molded into the material of which the insulating member is formed. The bushing 23, which may be made of brass or other suitable metal, is disposed intermediate the open ends of the bore of the insulating member 21, one end of the bushing forming an annular shoulder 25 adjacent an enlarged portion of the bore.

The train wire with which the electrical connector is associated comprises the usual copper conductor 27 covered with a durable insulating material 28, the conductor and the insulating material being provided with an outer weather-resistant covering 29, which may consist of flexible rubber tubing. As shown in Fig. 2 of the drawing, the end of the conductor 27 is exposed and projects a suitable distance beyond the insulation 28, a portion of which insulation is likewise freed from the tubing 29. The exposed end of the conductor 27 is thus adapted to be inserted through a suitable bore in a clamping nut member 30, which has formed on one end thereof a plurality of lugs 31 adapted to be swaged inwardly so as to grip the insulation 28, as is best shown in Figs. 3 and 5. On the opposite end of the clamping nut member 30 is formed an enlarged annular portion 33, which is adapted to be slidably fitted within the brass bushing 23 and is interiorly threaded to receive a similarly threaded end 34 of a butt contact member 35, the outer end 36 of which is adapted to engage a similar contact member of a counterpart electrical connector 40 when adjacent coupler devices are locked together, as shown in Fig. 1. Both the clamping nut 30 and the contact member 35 may be made of bronze.

The inner end 34 of the contact member 35 has a longitudinally disposed tapered bore 38 into which the free end of the conductor 27 is adapted to extend. Interposed between the end 34 and the conductor 27 is an elongated bronze sleeve member 39, which is made in the form of a frustum of a cone and is provided with a longitudinal slit 40 for enabling it to be tightly pressed against the conductor 27 as the clamping nut 30 and the contact member 35 are screwed together. It will be noted that the contact member 35 is provided

5 with a hexagonal portion 42 to which a wrench
10 may be applied when the parts are being assem-
15 bled. It will thus be seen that the means by
20 which the butt contact member 35 is detachably
25 secured to the conductor or train wire 27 serves
30 to insure a perfect electrical connection between
said elements.

10 A coil spring 44 is disposed around the contact
15 member 35 between the hexagonal portion 42
20 thereof and a pair of counterpart semicircular re-
25 tainer elements 45 abutting the bushing shoulder
30 25 for urging the contact member 35 outwardly.
35 The portion of the contact member 35 outwardly
40 of the hexagonal portion 42 is slidably guided in
45 a bushing 46 secured in an insulating member
50 47, which is mounted in the casing 15 and has a
55 sleeve portion 48 extending within and engaging
60 the cylindrical insulating member 21. The bush-
65 ing 46, which may be made of brass, is prefer-
70 ably molded into the "Bakelite" or other suit-
75 able substance of which the insulating member
80 47 is made. For insuring a tight joint, a gasket
85 49 may be interposed between a shoulder portion
90 50 of the insulating member 47 and the end
95 25 of the insulating member 21. The insulating
100 member 47 is held in place within the casing 15
105 by means of retainer screws 51, which extend
110 through suitably threaded apertures formed in
115 the casing 15 into an annular groove 52 formed
120 in the insulating member.

125 As a further feature of my invention, the elec-
130 trical connector is provided with sealing means
135 preventing access of dirt or moisture to the in-
140 terior of the casing. As shown in Fig. 2 of the
145 drawing, a flexible tubular shield 55 is provided,
150 which shield may be made of any suitable mate-
155 rial such as rubber composition and has formed
160 on one end thereof an annular flange 56, which is
165 secured within the casing 15 between an annular
170 shoulder portion 57 thereof and the end of the
175 cylindrical insulating member 21. The flexible
180 shield 55 surrounds the protective covering 29 of
185 the train cable and is so formed that, with the
190 outer portion 58 of the shield securely clamped
195 against the cable by means of a clamping mem-
200 ber 59, an annular fold 60 is provided in the
205 central portion of the shield, so that yielding move-
210 ment of the cable and associated contact ele-
215 ments with respect to the connector casing 50
220 may be effected during the coupling operation
225 without straining said shield.

230 At the end of the electrical connector 14 ad-
235 jacent the butt contact member 35 there is pro-
240 vided a flexible shield 62, which may be made of
245 the same material as the tubular shield 55. The
250 shield 62 comprises a flange portion 63 having an
255 interiorly disposed annular bead 64 adapted to
260 fit snugly within an annular groove formed in the
265 outer portion of the insulating member 47, and
270 an inclined flexible web portion 66, which ex-
275 tends outwardly from the flange portion 63 and
280 terminates in a relatively thick annular sealing
285 portion 67 surrounding the outer end of the con-
290 tact member 35. The annular sealing portion
295 67 of the shield 62 is adapted to grip the con-
300 tact member 35 in such a way that when the
305 contact member 35 is engaged by the counter-
310 part contact member of another coupler mecha-
315 nism as adjacent cars in a train are coupled
320 together, the resultant yielding movement of the
325 contact member 35 against the spring 44 will
330 cause flexing of the web portion 66, while the
335 sealing portion 67 will be distorted and retracted
340 with the contact member until the outer surface
345 75 of the sealing portion is engaged with the cor-
350 responding portion of the counterpart coupling
355 device. It will be noted that an annular chamfer
360 5 69 is formed in the outer surface of the sealing
365 portion 67 to accommodate displaced material as
370 the shield is distorted in the manner above ex-
375 plained. Similarly, with the flexible shield 62
380 secured in place upon the insulating member 47,
385 as shown in Fig. 2, the inclined web portion 66
390 defines a sufficient space 70 between the sealing
395 portion 67 and the insulating member to permit
400 the desired inward flexing.

405 From the foregoing description of the inven-
410 tion, it will be apparent that the electrical con-
415 nector constructed in accordance therewith is
420 adapted to be quickly assembled, and may be
425 readily taken apart if desired, as for inspection
430 or repairs. In addition, the electrical connector
435 is provided with flexible weather-resistant shield
440 means for preventing access of dirt or moisture
445 to the interior of the casing, which flexible means
450 is adapted to cooperate with the movable ele-
455 ments of the connector so that wear of said shield
460 means is reduced to a minimum.

465 Although a preferred embodiment of the in-
470 vention has been described in detail, it is not
475 my intention to limit its scope to that embodi-
480 ment or otherwise than by the terms of the ap-
485 pended claims.

490 Having now described my invention, what I
495 claim as new and desire to secure by Letters Pat-
500 ent, is:

505 1. In an electrical connector for a train line, in
510 combination, a casing having an opening there-
515 through, insulator means removably mounted in
520 said casing and having a bore adapted to receive
525 the end of the train line, a butt contact member
530 movably mounted in said insulator means and
535 extending outwardly of said casing, demountable
540 means securing said contact member in electrical
545 connection with said end of the train line, and a
550 flexible weather-resistant shield closing the open-
555 ing at one end of said casing and having a sealing
560 portion adapted to grip said contact member, said
565 sealing portion of the shield being adapted to flex
570 upon movement of said contact member so as to
575 maintain a tight fit therewith at all times for
580 insuring minimum wear.

585 2. An electric train line connector comprising,
590 in combination, a casing having an opening
595 through which the train line is adapted to ex-
600 tend, insulator means removably secured in the
605 opening and having a bore, a butt contact mem-
610 ber yieldably mounted in said bore, means freely
615 disposed within said insulator means and de-
620 tachably connecting said contact member with
625 said train line, a flexible weather-resistant sleeve
630 member having a portion surrounding and snugly
635 fitting said train line and another portion secured
640 within the opening at one end of said casing, and
645 a flexible weather-resistant shield closing the
650 other open end of said casing and having an
655 apertured portion encircling and tightly gripping
660 said contact member, said flexible sleeve member
665 and shield being adapted to yield upon movement
670 of said contact member and train line so as always
675 to prevent access of foreign matter into said cas-
680 ing.

685 3. In an electric train line connector, the com-
690 bination with a train wire having an insulating
695 cover, of a casing having a bore adapted to re-
700 ceive an exposed end of said wire, a clamping
705 member having a portion gripping said insulating
710 cover and an annular portion encircling said ex-
715 posed end of the train wire, a yielding tapered
720 sleeve element fitted on the end of said wire 75

within said annular portion, and a butt contact member yieldably mounted on said casing and provided with a portion having a tapered bore, said portion being forcibly interposed between said sleeve element and said annular portion of the clamping member for maintaining electrical connection between said contact member and said train wire.

4. In an electric train line connector of the type adapted to be coupled to a counterpart connector in combination, a casing having an opening, a butt contact member suitably mounted in said casing and extending outwardly through said opening, and a weather-resistant shield comprising a resilient ring portion having retainer

means for securing said shield to said casing, a flexible annular web portion sloping inwardly from said ring portion, and a relatively thick resilient sealing portion formed on said web portion and having an aperture through which said contact member projects, said sealing portion being adapted to tightly grip said contact member for preventing frictional wear of said portion during movement of said contact member in co-acting with the counterpart connector, and being also adapted to yield sufficiently during such movement to effect engagement of said sealing portion with that of the counterpart connector.

MORTIMER B. CAMERON. 15
